UNITED STATES PATENT OFFICE.

AMOS T. SHOWALTER, OF HAGERSTOWN, MARYLAND.

BALE-TIE-FORMING MACHINE.

1,046,661.

Specification of Letters Patent. Patented Dec. 10, 1912.

Application filed July 11, 1912. Serial No. 708,769.

To all whom it may concern:

Be it known that I, AMOS T. SHOWALTER, a citizen of the United States, residing at Hagerstown, in the county of Washington 5 and State of Maryland, have invented certain new and useful Improvements in Bale-Tie-Forming Machines, of which the following is a specification.

The present invention relates to a machine 10 for forming bale ties by cutting a continuous strand of wire into sections of suitable lengths and providing an eye upon one end of each section, whereby the two ends of the section may be quickly tied together.

15 An important object of this invention is to provide a machine of the above mentioned character, which is continuous, expeditious, and automatic in operation.

A further object of the invention is to 20 provide a machine of the above mentioned character, which is simple in construction, cheap to manufacture, and easy to operate.

Other objects and advantages of the invention will be apparent during the course 25 of the following description.

In the accompanying drawings forming a part of this specification and in which like numerals are employed to designate like parts throughout the same, Figure 1 is a 30 plan view of the machine, Fig. 2 is a side view of one of the cutting means, Fig. 3 is a side view of the machine, the rotating arm or support being arranged at right angles to the stationary track, Fig. 4 is a view similar 35 to Fig 3 and taken at a right angle to the same, the rotatable arm or support having one end thereof disposed near and spaced from the stationary track, Fig. 5 is a side view of retarding means for controlling the 40 feed of the wire, and, Fig. 6 is a detail section through means to prevent the improper rotation of holding and twisting elements.

In the drawings wherein, for the purpose 45 of illustration, I have shown a preferred embodiment of my invention, the numeral 6 designates a horizontal base, upon which is rigidly mounted an upstanding central bearing 7, having a vertical rotatable shaft 8 journaled therein.

50 The numeral 7' designates an upper bearing for holding the upper end of the rotatable shaft 8. The bearing 7' is supported by legs 8'. Rigidly connected with the vertical shaft 8 is a sprocket wheel 9, engaged by a 55 sprocket chain 10, which extends laterally to engage a sprocket wheel 11. This

sprocket wheel 11 is driven by a bevel gear 12, which in turn is driven by a bevel gear 13. Bevel gear 13 is shown as driven by a motor 14. 60

It is to be understood that the means shown for rotating the shaft 8 are employed to illustrate one way in which said shaft may be rotated and that any other suitable means may just as well be used. 65

Rigidly connected with the upper end of the shaft 8 is a preferably horizontal movable or rotatable arm or support, 15, to the ends of which are rigidly connected upstanding brackets or bearings 16 and 17, 70 which are forked at their upper ends to receive rollers 18, as shown.

The numeral 19 designates upstanding bearings which are rigidly connected with the arm or support 15 inwardly of and near 75 the bearings 16 and 17, as shown. Journaled through these bearings are horizontal wire holding and twisting elements or hooks 20. These elements 20 have inner hook ends 21 and are free to rotate with relation to the 80 arm 15 but cannot partake of perceptible longitudinal movement with relation thereto. Rigidly connected with the outer ends of the elements 20 are pinions 22, adapted to be moved into engagement with a curved 85 rack-bar track 23, which is attached to a horizontal support 24. The support 24 is held in its proper position by posts 25 or the like. Rigidly connected with the horizontal support 24 are upstanding brackets 26, the upper 90 ends of which overhang the rack-bar track 23 and have connection with a curved guide track 27, which is engaged by the rollers 18. It is thus seen that the rollers 18 and the guide track 27 serve to positively prevent 95 the pinions 22 from moving upwardly out of engagement with the rack-bar track 23, after the same have moved into engagement therewith. The pinions 22 are rotated when traveling in engagement with the rack-bar 100 track 23, whereby the elements 20 are accordingly rotated. Before and after the pinion 22 has traveled into engagement with the rack-bar track 23, the holding and twisting element 20 assumes a position so that the 105 hook end 21 thereof will be vertically disposed. In order that the pinion 22 may not be improperly rotated when not in engagement with the rack-bar track 23, whereby the hook end 21 will be moved out of its 110 vertical position, I provide a reciprocatory catch 20a, disposed near and below each of

the elements 20 and journaled through the 5 bearings which support the same. Each reciprocating catch has its outer end tapered or conically shaped, as shown at 21^a, for movement into a correspondingly shaped opening 22^a formed upon the inner end of the pinion 22. When the pinion 22 is moved to bring the hook end 21 of the element 20 in its vertical position, the tapered end 21^a 10 is forced into opening 22^a by a coil spring 24^a, which surrounds the reciprocating catch 20^a and has one end thereof in engagement with the bearing 19 and its opposite end in engagement with a ring 23^a, which is 15 rigidly attached to the reciprocating catch 20^a. The spring 24^a is of sufficient stiffness to prevent the accidental rotation of the pinion 22, but does not prevent said pinion being rotated when it engages the rack-bar 20 track 23, as the spring 24^a will then yield when the pinion 22 is rotated, since the outer end of the catch 20^a is tapered, as above explained.

The numeral 28 designates a continuous 25 strand of wire or the like, which is fed from a spool (not shown) of the same, and which is to be cut into sections of the desired length. Disposed opposite the rack-bar track 23 is an upstanding substantially inverted V-shaped bracket 29, provided in its 30 upper end with openings 30, through which is passed the wire. Connected with the bracket 29 is a housing 31, within which is pivotally mounted an element or finger 32, 35 which is adapted to clamp the wire against the upper end of the bracket 29, to retard or prevent the feeding movement of the wire. Connected with the lower end of the finger 32 is a retractile coil spring 33, which 40 normally holds said finger 32 in a position so that it will not prevent the free feeding movement of the wire. The finger 32 is swung in an opposite direction to clamp the wire against the upper end of the bracket 45 29 to retard the feeding movement thereof by a vertically inclined inwardly extending arm or rod 34, which is connected with the upper end of the finger 32. When one end of the arm 15 is moved above and into engagement with the arm or rod 34, it swings the free end thereof downwardly and causes the finger 32 to have clamping engagement with the wire 28 to retard the feeding movement thereof. It is thus seen that 50 automatically operated means are provided to retard the feeding movement of the wire. The strand of wire 28 is now passed through a stationary guide 35, which is mounted upon the upper end of the stationary vertical post 36, which is disposed near and spaced from one side of the bracket 29, as shown.

I provide means to thread the wire 28 55 into the hook ends 21 of the wire holding and twisting elements 20, during the con-

tinuous operation of the arm or support 15. Such means include upstanding rods 37, which are rigidly mounted upon the arm or support 15, as shown at 38. The rods 37 are curved longitudinally in a vertical 70 plane upwardly and downwardly and are also laterally curved or inclined in opposite directions, as best shown in Fig. 1. The free ends of these curved or hook-like rods 37 are disposed near the inner hook ends 75 21 of the elements 20. It is thus seen that as each of the rods 37 is moved into engagement with the section 39 of the wire 28, the wire will be guided or threaded by the rod 37 into the hook end 21 of the element 20. In this manner the wire is automatically 80 threaded into the hook ends 21 of the elements 20 during the continuous rotation of the arm or support 15.

Disposed inwardly of and near the wire 85 holding and twisting elements 20 are cutting means including pivoted cutters 40 having extensions 40', which are disposed upon opposite sides of the arm or support 15 and are swung in opposite directions with relation to each other to cut the wire. As clearly shown in Fig. 2, each of the cutters 40 is pivotally connected with a co-acting cutter 41, as shown at 42. That portion of the wire to be cut is caught between the 90 cutter 40 and the co-acting cutter 41, the same being cut when cutter 40 is swung in one direction, which takes place when the extension 40' is moved into engagement with a stationary trip 43. Attention is called to 95 the fact that the trip 43 is so arranged with relation to the rack-bar track 23, that the same will not move the cutter 40 until the pinion 22 has disengaged said track, as more clearly illustrated in Fig. 1. Connected 100 with the lower end of each extension 40' is a retractile coil spring 44, the upper end of which is attached to the arm 15. This spring serves to normally hold the cutter 40 in its inoperative position so that the wire 110 may be fed between the same and the co-acting cutter 41. Attention is called to the fact that when the section 39 of the wire is guided or threaded into the hook end 21 of the element 20, there is formed a section 45 of the wire, which has one end portion disposed between the cutters 40 and 41, whereby this portion of the wire will be cut when cutter 40 is moved by the trip 43. The right end portion of section 39 which is adjacent the right end of section 45, engages 115 behind the cutter 40, as shown, and is not cut but has an eye formed thereon by the rotation of the element 20. After the pinion 22 has traveled the entire length of the rack-bar track 23, this eye is formed, and when the pinion 22 disengages the track, the section 45 of the wire is cut. At a little before the time that the trip 43 moves the cutter 40, the arm 15 engages the rod 34, 120 125 130

to swing the finger 32, whereby the feeding movement of the wire 28 is retarded. This puts the sections 39 and 45 of the wire, under tension. The section 45 thus being 5 under tension and engaging the cutter 40 to the left, will automatically jump off of the hook end 21 when such section is cut by the cutting means disposed near the element 20 to the right.

10 The operation of the machine is as follows:—The wire 28 is passed through the openings 30 of the bracket 29 and through the guide 35. An eye is now formed by hand upon the free end of the wire, which 15 eye is placed in the hook end 21, the portion of the wire which is adjacent this eye being arranged in engagement with the back of the cutter 40. The shaft 8 is now rotated. When the element 20 moves into proximity 20 to the section 39 of the wire, the curved rod 37 will thread the same into the hook end 21 of the element 20. The right end of section 45 is arranged between the cutters 40 and 41 while the right end of section 39 25 engages the back of the cutter. The pinion 22 is now moved into engagement with the rack-bar track 23, whereby the element 20 is rotated and an eye is formed or twisted upon the right end of section 39. When the 30 pinion 22 disengages the rack-bar track, the stationary guide 43 swings the cutter 40, whereby the right end of section 45 is cut and said section 45 with the eye formed upon one end thereof, will automatically 35 jump off of the arm 15 and out of the hook end 21. The automatic springing or jumping of the section 45 is due to the fact that this section is under tension, as hereinabove explained. The operation of the machine is 40 continuous and automatic. Attention is called to the fact that when the pinion 22 has traveled the entire length of the rack-bar track 23, and is moved out of engagement therewith, the hook end 21 of the element 45 will be vertically disposed. The 45 spring 24^a will now force the reciprocatory catch 20^a into the opening 22^a, whereby said pinion is prevented from being rotated until it again engages the rack-bar track 23. The 50 catch 20^a does not prevent the track 23 from rotating the element 20 when the pinion 22 travels in engagement with said track.

It is to be understood that the form of my invention herewith shown and described is 55 to be taken as a preferred example of the same and that certain changes in the shape, size, and arrangement of parts may be resorted to without departing from the spirit of the invention or the scope of the subjoined claims.

Having thus described my invention, I claim:—

1. In a machine of the character described, the combination with a support, of 65 a rotatable arm mounted upon the same,

wire holding and twisting elements mounted upon the rotatable arm near the ends thereof, means to rotate the wire holding and twisting elements during the rotation of the arm, wire cutting means disposed near 70 the wire holding and twisting elements, means to operate the wire cutting means during the rotation of the arm, means to guide the wire into engagement with said wire holding and twisting elements, and 75 means to rotate the arm.

2. In a machine of the character described, the combination with a supporting structure, of a rotatable support mounted upon the same, wire holding and twisting 80 elements mounted upon the rotatable support near the ends thereof, means to rotate the wire holding and twisting elements during the rotation of the support, wire cutting means disposed near the wire holding 85 and twisting elements, means to operate the wire cutting means during the rotation of the support, means to guide the wire into engagement with said wire holding and twisting elements, means to rotate the support, and means to retard the feeding movement of the wire when the support assumes 90 a certain position.

3. In a machine of the character described, a rotatable arm, wire holding and 95 twisting elements mounted upon the rotatable arm and extending longitudinally thereof, means to rotate said elements with relation to the arm during the rotation of said arm, wire threading means mounted upon 100 the arm and disposed near said elements, wire cutting means mounted upon the arm and disposed near said elements, means to operate the wire cutting means during the rotation of the arm, and means automatically operated by said arm to retard the feeding movement of the wire when the arm 105 assumes a certain position.

4. In a machine of the character described, a movable support, spaced wire 110 holding and twisting elements connected with the movable support and movable with relation thereto, means to move the wire holding and twisting elements with relation to said support during the movement of said support, wire threading means to conduct the wire into engagement with the wire holding and twisting elements, wire cutting means, means to operate the wire cutting means during the movement of said support, and clamping means automatically operated by the movable support to retard the feeding movement of the wire. 115

5. In a machine of the character described, a supporting structure, a rotatable 120 support mounted thereon, wire holding and twisting elements mounted upon the rotatable support to rotate with relation thereto, means to rotate the rotatable support, means 125 to rotate the wire holding and twisting ele- 130

ments during the rotation of said rotatable support, wire guide elements attached to the rotatable support for movement therewith and arranged near the wire holding and 5 twisting elements, a stationary wire guide element mounted upon the supporting structure to hold the wire so that a portion thereof will be successively engaged by the wire guide elements attached to the rotatable 10 support, and means to cut the wire during the movement of the rotatable support.

6. In a machine of the character described, a supporting structure, a rotatable support mounted thereon, wire holding and 15 twisting elements mounted upon the rotatable support to rotate with relation thereto, means to rotate the rotatable support, means to rotate the wire holding and twisting elements during the rotation of said rotatable 20 support, curved wire guide elements attached to the rotatable support near the wire holding and twisting elements and having their free ends extending in opposite directions, a relatively stationary wire guide mounted 25 upon the supporting structure to hold the wire so that a portion thereof will be suc-

cessively engaged by the wire guide elements attached to the rotatable support, and means to cut the wire during the movement of the rotatable support.

7. In a machine of the character described, a supporting structure, a rotatable support, wire holding and twisting elements mounted upon the rotatable support to rotate with relation thereto, means to rotate 30 said rotatable support, means to rotate the wire holding and twisting elements, means to guide the wire to the wire holding and twisting elements, cutting devices mounted upon the rotatable support near the wire holding and twisting elements and including pivoted cutting elements, and a stationary trip to move the pivoted cutting elements during the movement of the rotatable support.

In testimony whereof I affix my signature in presence of two witnesses.
